UNITED STATES PATENT OFFICE.

WILLIAM R. DUNCAN, OF CHICAGO, ILLINOIS.

AUTOMATIC STOP FOR TALKING MACHINES.

Application filed March 2, 1923. Serial No. 622,317.

To all whom it may concern:

Be it known that I, WILLIAM R. DUNCAN, a citizen of the United States, residing at Chicago, in the county of Cook and State 5 of Illinois, have invented certain new and useful Improvements in Automatic Stops for Talking Machines, of which the following is a specification.

This invention relates to means for stopping a phonograph when the record has been 10 finished and is particularly applicable to phonographs or talking machines of the Edison type.

The objects of this invention are to provide 15 a simple mechanical device for automatically stopping a phonograph motor at a predetermined time; to provide a device of this character which may be actuated or controlled by the floating weight of an Edison reproducer; to provide means for increasing 20 the available power for actuating the tripping mechanism; and in general to provide such an improved stop mechanism as will be described more fully hereinafter.

25 In the accompanying drawings illustrating this invention—

Figure 1 is a plan view or a portion of a phonograph with my stop applied thereto, parts being shown in section or diagrammatically;

Figure 2 is a side view of the same;

Figure 3 is an enlarged front elevation of the trip mechanism;

Figure 4 is a view similar to Figure 3 but 35 with parts shown in section;

Figure 5 is a sectional view taken on the line 5—5 of Figure 3; and

Figure 6 is a detail of the brake mechanism.

40 In the Edison type of phonograph there is a floating weight which forms a part of the reproducer and which carries the stylus. When the stylus reaches the end of the groove in the record, the free end of the 45 weight is raised and moves laterally with respect to the reproducer or horn. It is this movement which I utilize for the purpose of controlling the brake mechanism. As shown in these drawings the horn 7 which is pivoted and swings in the well known manner in the Edison talking machine is provided with a reproducer 8 having the usual floating weight 9. This weight is pivoted at 10 on a vertical pivot and is provided with a rear-

wardly extending pin or arm 11 which is 55 adapted to swing in a horizontal plane with the weight.

A casing 12 is mounted on the horn 7 and is preferably positioned adjacent to the outer edge of the turntable 13. This casing is conveniently held by means of an arm or bracket 14 which is secured to a clamp 15 which engages with the horn 7. A plunger 16 is mounted in the casing 12 and is pressed downwardly by a spring 17. The foot 18 60 of this plunger is preferably made of felt or the like for engagement with the brake trip lever 19. The upper end of the plunger is pivoted at 20 to one arm of a lever 21, this lever being fulcrumed at 22 in the casing. 65 The inner end of this lever is provided with a hook or catch 23 which coacts with a similar hook 24 on a lever 25 for holding the plunger in raised position as shown in Figure 4. The lever 25 is pivoted at 26 and is 70 weighted or provided with a projection 27 which tends to move the hook 24 into engaging position by gravity. The lever 25 projects outwardly at one end of the box or casing 12 and is adapted to be struck by 75 a weight 28 on the end of a lever 29 which lever is pivoted at 30 to the casing. This lever has a thumbpiece or extension 31 which is adapted to engage the outer end of the lever 21 for pressing the same downwardly 80 to raise the plunger and the bottom of the casing is also provided with a projection or finger piece 32 for convenience in pressing the lever down. The lever 29 has a pawl or 85 detent 33 which engages with a catch 34 on the end of a rod 35 which extends through 90 the casing and projects forwardly to a point adjacent to the end of the arm 11. This rod is supported by a bracket or bearing 36 from 95 the clamp 15 and has a downwardly projecting finger 37 which is secured thereto and is adapted to be engaged by the arm 11 for turning or oscillating the rod 35.

When the stylus reaches the end of the 100 groove in the record 38, the floating weight will swing laterally with respect to the horn or reproducer and cause the arm 11 to swing the arm 37 and rock the shaft 35 which will cause the catch 34 to disengage 105 from the detent 33, thereby allowing the weight 28 to drop and strike the lever 25 which will cause the hook or catch 24 to be released from the catch 23 thereby permit-

ting the plunger to move downwardly under the action of the spring 17. It will be understood that the power supplied by the movement of the weight 9 is very small but it is sufficient to release a catch of the character shown which catch is not subjected to the action of the plunger spring. The falling of the weight 28 is, however, sufficient to actuate the second catch which directly holds the spring pressed plunger.

In order to accentuate or add to the power of the arm 11, I provide a spring 39 which is mounted on a support 40 on the casing 12 and pressed against the arm 11. This pressure may be adjusted by a screw 41 as shown in Figure 5. When the stylus leaves the end of the groove this spring will tend to make the lateral movement of the floating weight more positive and insure the operation of the trip mechanism. Any suitable brake may be operated or controlled by the plunger 16 but I have shown one form of brake which is applicable for this purpose. As the details of this brake form no part of the present invention, it will not be necessary to describe the same, but a trip lever 19 is provided for actuating the brake mechanism 43. This lever is pivoted at 44 to the table 45 and has one arm 46 curved to correspond with the travel of the horn 7 and plunger 16, so that the plunger will always be in position to strike this end of the lever. When the plunger 16 strikes the lever 46, it releases the brake 47 which engages the turntable 13 to stop the same. The brake is also provided with a reset lever 48 which operates in the usual manner for releasing the brake.

From this description it will be seen that I provide a simple arrangement whereby the power furnished by the movement of the floating weight may be increased or augmented in order to provide suitable mechanical actuating mechanism for stopping the machine.

Having thus described my invention, what I claim and desire to secure by Letters Patent is:

1. A stop for phonographs having reproducers provided with floating weights, comprising a brake mechanism having a trip lever, a spring plunger for engagement with said lever, a catch for holding the plunger in raised position, a weight for actuating said catch, a second catch for holding the weight in raised position and means actuated by the floating weight of the reproducer, for tripping the last named catch.

2. A stop mechanism for a phonograph having a reproducer provided with a floating weight, comprising a member for operating a brake, a catch for holding said member in raised position, a trigger latch for

engagement with said catch, a weight for actuating said latch, a catch for holding said weight in raised position, a trigger latch for engagement with said catch and means actuated by the floating weight of the reproducer for releasing the last named latch, whereby the parts will operate substantially as described.

3. The combination with a spring actuated stop member for phonographs, of a locking device for holding the same in normal position, a weight for actuating said locking device, an auxiliary locking device for holding the weight in raised position, and a talking machine reproducer having a floating weight which releases said auxiliary device when said weight has moved to a predetermined position.

4. In a device of the character set forth, the combination with a plunger, of a spring for actuating said plunger, a lever having a catch at one end for holding the plunger in raised position, a weight adapted to engage with the last named lever for releasing the catch, a pivoted arm carrying said weight, one end of said arm being adapted to engage with the first named lever for returning the lever to normal position, a detent on said arm, a latch for engagement with said detent, a rod supporting said latch, an arm on said rod, and a reproducer having a floating weight with an arm adapted to engage with said last named arm for rocking the rod.

5. The combination with a phonograph horn, of a bracket, a casing supported by said bracket, a plunger mounted in said casing, a spring tending to press the plunger downwardly, a lever pivotally mounted in the casing and engaging with the plunger, one end of said lever projecting out through the casing and the other end being provided with a catch, a second lever pivotally mounted in the casing and having a latch for engagement with said catch, a weight for striking the last named lever to release the latch, a lever pivotally mounted on said casing, said lever having the weight secured to one end thereof, the other end of the lever projecting outwardly to form a thumbpiece which is adapted to engage with the projecting end of the first named lever, a detent on said last named lever, a catch for said detent, a rock shaft supporting said catch, an arm on said shaft and a reproducer having a swinging weight with an arm adapted to engage with the last named arm for rocking the shaft.

6. The combination with a phonograph having a floating weight, of a weight, a trip mechanism for supporting the weight, means for actuating the trip mechanism by the floating weight when the stylus has left the end of the groove in the record, a spring pressed member, a trip mechanism for hold-

ing said member in raised position, said trip mechanism adapted to be actuated by the weight for releasing the spring pressed member.

5 7. The combination with a phonograph having a reproducer with a floating weight, of stop means adapted to be actuated by the movement of said floating weight relative to the reproducer and means for supplementing the actuating power of the floating weight in order to operate the stop means.

19 8. The combination with a phonograph, of a brake mechanism having a trip arm positioned adjacent to the horn and extending across the path of the horn and a stop device carried by the horn and adapted to be actuated by the reproducer for engagement with said trip lever, the arrangement being such that the stop device will always 20 be in position to engage with the lever.

15 9. The combination with an Edison phonograph horn, of a spring plunger,

means for automatically releasing the plunger at predetermined times, a brake mechanism including a trip lever extending 25 across the path of the horn and adapted to be engaged by the spring plunger in any position of the horn.

10. The combination with an Edison phonograph, of a brake for engagement with 30 the turntable, a trip lever for releasing said brake, an operating member carried by the horn and adapted to engage with said trip lever and means for automatically actuating said operating member when the stylus 35 reaches the end of the groove in the record.

11. The combination with the floating weight of an Edison reproducer, of a spring for assisting the lateral movement of the weight with respect to the reproducer when 40 the stylus passes from the end of the groove in the record.

WILLIAM R. DUNCAN.
